INSULATOR FOR CRANK CASES AND OIL PANS

Filed March 5, 1929

Fig. 4.

INVENTOR
WILLIAM F WALTERS

BY

Andrew E. Carlson
ATTORNEY

UNITED STATES PATENT OFFICE

WILLIAM F. WALTERS, OF MINNEAPOLIS, MINNESOTA

INSULATOR FOR CRANK CASES AND OIL PANS

Application filed March 5, 1929. Serial No. 344,425.

This invention relates to internal combustion engines, and the primary object is to provide simple, efficient, and practical means for insulating the crank case and oil pan against low temperatures and to thereby retain the lubricant at a relatively high temperature through periods when the engine is idle, and by reason of which the oil will not congeal as readily as would otherwise be the case, the engine will start more easily, and the lubricant will be in a condition that will permit it to be fed immediately to other parts of the motor by the usual oil pump. More particularly the object is to provide insulating chambers at the sides and bottom of the oil reservoir, which chambers are sealed so as to be air tight, and from which the major portion of the air has been drawn to effect partial vacuums therein, thereby more effectively insulating the reservoir and preventing the penetration of frost through its walls. I am aware of prior art devices in which the crank case or oil pan of a motor are provided with auxiliary surface chambers through which fluid mediums are circulated either for heating or cooling purposes, but the devices of that nature that have come to my attention do not recognize or answer the problem with which I am concerned, as they do not concern themselves with maintaining the previously acquired temperature of the lubricant, but rather provide means for altering the lubricant temperature by running the engine, which, of course, in no way helps to start the engine, which is the serious objection that this device is designed to overcome, at least in a large and effective degree.

In the accompanying drawing, which illustrates a preferred embodiment of the invention:

Fig. 1 is a sectional elevation taken transversely through the lower portion of an internal combustion engine having my invention applied thereto.

Fig. 2 is an enlarged detail section of the water trap and oil drain as shown in Fig. 1, and also more clearly showing the weld seam joint at the edges of the insulation chamber forming plates.

Figs. 3 and 4 are enlarged detail views of

the drains and stoppers for the bottom and side chambers, respectively.

Referring to the drawing more particularly and by reference characters, A designates the engine block of an internal combustion engine having a crank shaft B operating in an oil or lubricant reservoir C formed by the crank case D and oil pan E all of common and well known construction and arrangement.

The oil pan E may be of standard or special construction, but in either event is supplemented by a pair of spaced plates or walls 4 and 5, of similar shape to and forming chambers 6 and 7 with the pan E. The pan forming plates 4 and 5 are successively deeper than the pan E, and their flanges 8 and 9 are welded together and to the flange 10 of the pan E, as at 11, so as to form an air tight surrounding seam for the chambers 6 and 7. A drain pipe 12 extends from the bottom of the pan E, down through the plates 4 and 5, and is welded or otherwise tightly secured in the members E, 4 and 5, so as to virtually constitute a part thereof. This pipe 12 is provided with a drain plug 13, which, when removed, permits the oil pan E to be drained, as, for instance, when it is found necessary to replenish the chamber C with new and fresh oil. It may also be noted, however, that the pipe 12 may also serve in the additional capacity as a water trap, as it comprises a small receptacle in the bottom of the lubricant chamber, and, when occasionally opened for a moment, will discharge the water that has settled therein.

A second plug, 15, having two sets of threads 16 and 17, screws into integral bearings or sockets 18 and 19 of the plates 4 and 5, as shown particularly in Fig. 3. The object of this plug is to permit draining of the chambers 6 and 7 should moisture accumulate therein, and to provide means for withdrawing the air, to form as complete a vacuum as possible in the chamber, to thus increase the insulating effect of the chambers 6 and 7. It may here be noted that the boss 19 may be externally threaded, as at 20, to receive a suction creating device while the plug 15 is held in readiness by a suitable wrench, operating

in the device, to be secured in place while the chambers 6 and 7 are exhausted.

The side walls of the crank case D are insulated in a similar manner as above explained in connection with the oil pan E, in this instance plates 21 and 22 being welded together about their edges and in turn secured to the case D to form insulating chambers 23 and 24, having a common plug 25 serving in the same capacity as the previously noted plug 15. It may here be mentioned that it is found preferable to treat the surfaces of the members D, E, 4, 5, 21, and 22, as by enameling, prior to being assembled, and this assists in maintaining the partial vacuum conditions in the insulation chambers and prevents the penetration of these plate members by frost, thus further carrying forward the primary objects of the invention as hereinabove set forth.

It is understood that suitable modifications may be made in the general design and structural details of the invention, as herein disclosed, provided, however, that such modifications come within the spirit and scope of the appended claims.

Having now, therefore, fully shown and described my invention, what I claim to be new, and desire to protect by Letters Patent is:

1. The combination with an oil reservoir of an internal combustion engine, of a pair of spaced plate members secured externally to and forming chambers with a part of the reservoir, and means for sealing said chambers whereby they may maintain a partial vacuum condition when air has been drawn therefrom.

2. The combination with an oil reservoir of an internal combustion engine, of a pair of spaced plate members secured externally to and forming chambers with a part of the reservoir, said chambers being normally exhausted and sealed whereby to maintain a partial vacuum therein, and a plug securable in the plate members and removable to open both chambers.

3. The combination with an oil reservoir of an internal combustion engine, of a pair of spaced plate members secured externally to and forming chambers with a part of the reservoir, said chambers being normally exhausted and sealed whereby to maintain a partial vacuum therein, and a plug securable in the plate members and removable to open both chambers, and a coat of substantially imperforable material applied to the plate members.

4. The combination with an oil reservoir of an internal combustion engine, of a pair of spaced plate members secured externally to and forming chambers with a part of the reservoir, said chambers being normally exhausted and sealed whereby to maintain a partial vacuum therein, and a plug securable

in the plate members and removable to open both chambers, and a coat of enamel applied to each of the plate members.

5. The combination with an oil reservoir of an internal combustion engine, of a pair of spaced plate members secured under the reservoir to form insulating chambers thereunder, a tubular member extending from the reservoir down through the chambers to drain the reservoir, said tubular member having a stopper at its lower end whereby it will serve as a receptacle trap for water and sediment in the oil of the reservoir.

6. The combination with an oil reservoir of an internal combustion engine, of a pair of spaced plate members secured under the reservoir to form insulating chambers thereunder, a tubular member extending from the reservoir down through the chambers to drain the reservoir, and a stopper securable in the plate members for opening the insulating chambers.

7. The combination with the oil pan of an internal combustion engine, of a pair of successively deeper pan members secured under the oil pan, to form spaced insulating chambers therewith, said oil pan and members having contiguous flange portions welded together, and means for respectively draining the oil pan and chambers.

8. The combination with the oil pan of an internal combustion engine, of a pair of successively deeper pan members secured under the oil pan, to form spaced insulating chambers therewith, said oil pan and members having contiguous flange portions welded together, and a tubular drain member extending from the oil pan through the pan members but sealed from communication with the insulating chambers.

Signed this 2nd day of March, 1929, at Minneapolis, Minnesota.

WILLIAM F. WALTERS.
